UNITED STATES PATENT OFFICE

134,297

DESIGN FOR A NOVELTY CONTAINER

Leon Cardon, Jamaica, and Carl Marc,
Laurelton, N. Y.

Application December 27, 1940, Serial No. 97,627

Term of patent 3½ years

To all whom it may concern:

Be it known that we, Leon Cardon and Carl Marc, both citizens of the United States, residing, respectively, at Jamaica, in the county of Queens and State of New York, and at Laurelton, in the county of Queens and State of New York, have invented a new, original, and ornamental Design for a Novelty Container, of which the following is a specification, reference being had to the accompanying drawings, forming part thereof.

Fig. 1 is a perspective view of a novelty container, showing our new design.

Fig. 2 is an edge view thereof.

Fig. 3 is a perspective view thereof, in open position.

We claim:

The ornamental design for a novelty container, substantially as shown.

LEON CARDON.
CARL MARC.
